Patented Sept. 12, 1922.

Inventor
Engelbert Nicolussi

By his Attorney

Marvin Davis

UNITED STATES PATENT OFFICE.

ENGELBERT NICOLUSSI, OF GLENDALE, MONTANA, ASSIGNOR OF ONE-HALF TO
CHARLES NICOLUSSI, OF CHICAGO, ILLINOIS.

CULINARY IMPLEMENT.

Application filed March 9, 1922. Serial No. 542,359.

To all whom it may concern:

Be it known that I, ENGELBERT NICOLUSSI, a citizen of the United States, residing at Glendive, in the county of Dawson and State 5 of Montana, have invented certain new and useful Improvements in Culinary Implements, of which the following is a specification.

This invention relates to implements employed in culinary operations, particularly to that department in which fruits and vegetables are cleansed and otherwise prepared for use.

An object has been to construct a simple, 15 practical device adapted to be manually controlled and to perform its several functions in an efficient manner.

A further object has been to provide a single piece of metal, with definite conformations, each having a specific purpose, the 20 whole being arranged as a combination device adapted to be manufactured at a small cost.

These and other objects are attained by 25 the novel combination and arrangement of integral parts, hereinafter described and shown in the accompanying drawing, forming a material part of this disclosure, and in which:—

30 Figure 1 is a top plan view of the device.
Figure 2 is a side elevational view of the same.

Figure 3 is an enlarged fragmental sectional view taken on line 3—3 of Figure 1.
35 Figure 4 is a plan view of one of the raised elements, drawn to an enlarged scale.

Figure 5 is a sectional view of the same taken on line 5—5 of Figure 3.

40 Figure 6 is a transverse sectional view taken on line 6—6 of Figure 1.

Referring to the drawing in detail, the numeral 10 represents, in general, a flat piece of relatively thin metal, forming a base element from which a plurality of 45 spaced projecting elements 11 are raised.

These projections, in the process of forming, are sheared through the base a distance slightly less than that of the diameter of the projection at its base, thus forming an opening 12, and due to the drawing of the metal, a cutting edge 13 is automatically produced.

50 Referring to Figures 3 and 5, it will be seen that the projections or grater elements comprise two generally spherical portions

14 and 15 of different diameters, the upper 55 portion 14 being employed when it is desired to grate or reduce food materials to relatively fine particles, a light pressure only being required. A coarser product is obtained by using sufficient pressure to force 60 the material downward on to the larger spherical element 15. In either case, the grated material is ejected from the base 10 through the opening 12.

Side plates 16 and 17, integral with the 65 base 10, are disposed downwardly and longitudinally of the base, serving as a handle element and stiffening the plate.

At the opposite end of the plate, is formed a tapered semi-circular member 18, having 70 side elements 19 and 20, arcuately curved, the end portion 21, forming an element adapted to enter and cut when rotated a cylindrical portion or core, as from an apple, the end 21 being well adapted for 75 removing defective spots from vegetables and fruits or cutting the eyes from potatoes, pine-apples and the like.

On the upper side of the tapered member 18, is a longitudinal raised element 22, 80 sheared through the stock at one side, forming a narrow opening 23, the raised lip being bevelled on the outer surface to form a cutting edge 24 adapted for paring or slicing purposes, the cuttings passing through the 85 opening 23 into the concave inner surface of the coring member.

The opposite ends of the implement are cut diagonally for appearance and an opening 25 is provided for hanging when not 90 in use.

Although the foregoing is descriptive of the preferred embodiment of the invention, it will be apparent that minor changes may be made in its construction, without the exercise of invention or conflicting with the scope of the claims hereto appended.

Having thus described my invention, what I claim as new and desire to secure by Letters Patent, is:—

100 1. A culinary implement comprising a grater consisting of a plurality of uniformly sized annular projections forced upwardly from a base plate, said projections having the form of two semi-spherical bodies of 105 unlike diameters arranged one above the other and separated from said base plate by an opening whose length approximately

equals that of the diameter of the largest sphere, said spherical projections being adapted to produce a fine or coarsely divided product, according to the pressure applied to the article being grated.

2. A culinary implement comprising a flat sheet of metal having flanged edges, a handle extending therefrom, and a plurality of upstanding projections having openings directed towards one side of said sheet, the mentioned openings being proportioned to produce particles of various magnitude when used as a grater depending upon the depth

said projections are entered into the substance operated upon.

3. A culinary implement comprising a flat sheet of metal having raised abrading elements presenting profiles formed of two distinct curves of different radii, the upper, outermost curve being the smaller, said elements being cut angularly to produce shearing edges and leading to openings therebelow extending through said sheet.

In witness whereof I affix my signature.

ENGELBERT NICOLUSSI.
